UNITED STATES PATENT OFFICE.

EDWARD FULDA, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,378,020.

Specification of Letters Patent. Patented May 17, 1921.

Application filed March 17, 1919. Serial No. 283,066.

To all whom it may concern:

Be it known that I, EDWARD FULDA, a citizen of the United States, and a resident of New York, in the county of New York and State of New York, have invented certain new and useful Improvements in Metal Wheels, of which the following is a specification.

My invention relates to that class of 10 wheels in which a sheet metal disk or plate having rim, hub and web or spoke parts all of one plate of metal is employed in the construction of the wheel either alone or in combination with a separate rim or felly 15 engaging the edge or edges of the disk or disks used in the construction.

The object of the invention is to produce a wheel of the above general character having great strength, simplicity and cheapness 20 of construction, together with great resistance to load and torsional strains.

A further object is to provide a construction of disk itself that may be conveniently 25 and cheaply used in the construction of metal wheels of the disk type by employing one or more of said disks in any desired way and which disk shall embody in its construction means for strengthening or reinforcing the wheel against the effects of torsional 30 strains.

To these ends my invention consists in the construction of disk or plate embodying strengthening tongues or struts as herein-after described.

35 The invention further consists in the manner of combining said disk with the rim to produce a wheel of great strength.

The invention further consists in a wheel 40 constructed, as hereinabove described, from a single disk with suitable rim as hereinabove more particularly described and claimed.

In the accompanying drawings:

Figure 1 is a side elevation of a form of 45 wheel embodying my invention and having my improved form of disk embodied in its construction.

Fig. 2 is a cross-section of said wheel on the line A—A Fig. 1.

Fig. 3 illustrates a sheet metal blank cut 50 to form suitable for a disk embodying my invention.

Fig. 4 shows a modification.

Referring to the drawings, 1 indicates the body, web or spoke portion proper of the

disk or plate, 2 the rim or edge part and 3 the hub portion perforated as shown for the 55 reception of the axle and bearing boxes, at which part 3 said disk may, in the construction of the wheel, be reinforced by a suitable attached hub bolted or otherwise secured 60 at opposite faces thereof after the usual manner employed in wheel constructions.

4 indicates a separate rim which in the preferred construction of wheel embodying my invention, is provided with the inwardly 65 turned flanges 5 at its edges. My invention, however, is not limited to this particular construction of rim but may be realized with other forms of metal rim with which my improved construction of disk is suitably 70 combined.

The edge of the disk when combined with the rim, engages the inner surface of said rim to receive the load and, at the engaging edge, is preferably formed, as indicated, 75 with the wings or ears 6 forming a transversely extending bent edge of the disk. These ears preferably extend in opposite directions from the plane of the disk and serve for attachment of the rim to the disk by 80 unions made between them and the inner surface of the disk in any desired way as by spot welds or otherwise.

As will be seen in the construction of wheel shown, which illustrates the simplest 85 way of embodying my improved disk therein, said disk receives the rim on its edge on a circumferential line intermediate the edges of the rim. The disk may be located centrally of the edges, thus giving an overhang 90 of the rim equal at both sides of the disk or it may be located at one side of the center, thus giving a larger overhang on one side than on the other which is sometimes desired. The said wings or ears are indicated 95 in Fig. 3, the line of bend being shown by the dotted line 7.

8 indicates metal tongues cut out of the body of the disk or plate integral therewith and bent to one side of the plane of the disk 100 to engage the rim at their free ends out of the general plane of the disk and thereby form struts or effecting practically a dishing of the wheel, whereby resistance to torsional strains tending to collapse the wheel 105 is resisted. To form a double dishing the said tongues are bent in opposite directions from the plane of the disk. At their free

ends they engage the rim preferably at or near its edges in any desired way. When the rim is formed with the inwardly turned circumferential edge the tongues may be secured to the inside of the flange by spot welding or otherwise, their extreme ends being bent over if desired, under the inside of the rim as shown in Fig. 4 and welded thereto. If desired the bent over ends may be dispensed with and the union made with the flange 5 only as indicated in Fig. 2. Obviously a number of the disks might be employed in the construction of the wheel, the planes of the disks being displaced with relation to one another axially with the wheel. The new form of disk, however, lends itself particularly to use in making up a wheel of effective strength and cheaply by employing but one disk.

20 If desired the struts 8 may be twisted at any point of their length so that their edges are presented to the side of the wheel rather than their flat sides as shown.

What I claim as my invention is:—

25 1. In a wheel of the character described, a sheet metal disk having its edge bent over at intervals to engage the inner surface of the rim and having at intermediate points tongues cut out of the body of the disk and bent to one side of the plane thereof and engaging the rim to act as struts to resist torsional strains.

30 2. In a wheel of the character described, the combination of a metal rim, a disk disposed with the plane of the disk intermediate the edges of the rim and engaged at its

edge in the plane of the disk with said rim to sustain the load, said disk having also tongues bent in opposite directions from the plane of the disk at points approaching the hub and connected at their free ends to the rim at its edges.

3. In a wheel of the character described, the combination with a rim having an inwardly turned flange at each edge and a sheet metal disk disposed with the plane of the disk intermediate the edges of the rim, said disk being engaged with the inner surface of the rim in the vertical plane of the disk to receive and support the load in said plane, said disk being also provided with transversely bent tongues bent from the plane of the disk at points near the hub and connected at their free ends to said flanges as and for the purpose described.

4. In a wheel of the character described, the combination with a metal rim having inwardly turned flanges at its edges, a disk having a transversely extending bent edge engaged with the inner surface of the rim and provided with tongues bent in opposite directions from the plane of the disk and secured at their free ends to the inwardly turned flanges.

Signed at New York, in the county of New York and State of New York, this 15th day of March, A. D. 1919.

EDWARD FULDA.
